Patented Apr. 1, 1975

234,701

AUTOMOBILE STEREO TAPE PLAYER

Maurice H. Kraines, Beverly Hills, Calif., assignor to
Kraco Enterprises, Inc., Compton, Calif.

Filed Nov. 21, 1972, Ser. No. 308,421

Term of patent 14 years

Int. Cl. D14—01
U.S. Cl. D26—14 B

FIG. 1 is a perspective view of the front and one side of an automobile stereo tape player showing my new design;

FIG. 2 is a side elevation, taken from the opposite side of FIG. 1;

FIG. 3 is a front elevation thereof;

FIG. 4 is a bottom plan view thereof; and

FIG. 5 is a rear elevation thereof.

I claim:

The design for an automobile stereo tape player, substantially as shown and described.
